(57) **CLAIM**

The ornamental design for a radio faceplate, as shown and described.

DESCRIPTION

FIG. 1 is a perspective view of a radio faceplate;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines that are immediately adjacent to the claimed areas represent the bounds of the claimed design, while all other broken lines are directed to environment and are for illustrative purposes only; the broken lines form no part of the claimed design.

1 Claim, 5 Drawing Sheets
